UNITED STATES PATENT OFFICE

103,460

DESIGN FOR A VEHICLE BODY

Neil P. Larsen, Cleveland, Ohio, assignor to
American Coach & Body Company, Cleveland,
Ohio, a corporation of Ohio

Application April 20, 1936, Serial No. 62,216

Term of patent 14 years

To all whom it may concern:

Be it known that I, Neil P. Larsen, a citizen of the United States, residing at Cleveland, in the county of Cuyahoga and State of Ohio, have invented a new, original, and ornamental Design for a Vehicle Body, of which the following is a specification, reference being had to the accompanying drawings, forming a part thereof.

In the drawings Fig. 1 is a perspective view of the body embodying my design, Fig. 2 is a front view of the body, and Fig. 3 is a rear view of the body. The dominant feature of the design is the integral construction of the cab and storage com-

partments, the storage compartment being offset inwardly near the midportion, and having the side walls tapering inwardly above the offset and merging with the top in curved surfaces.

The side of the body opposite that shown in Fig. 1 is substantially the same as that illustrated, except for the fact that there is a conventional door in the driver's cab.

I claim:

The ornamental design for a vehicle body as shown and described.

NEIL P. LARSEN.
